UNITED STATES PATENT OFFICE.

JAMES C. THOMPSON, OF GOLCONDA, ILLINOIS.

ROTARY ENGINE.

1,259,318.

Specification of Letters Patent. Patented Mar. 12, 1918.

Application filed August 16, 1917. Serial No. 186,556.

To all whom it may concern:

Be it known that JAMES C. THOMPSON, a citizen of the United States, residing at Golconda, in the county of Pope and State 5 of Illinois, have invented certain useful Improvements in Rotary Engines, of which the following is a specification, reference being had therein to the accompanying drawing.

10 The present invention has reference generally to improvements in steam engines and more particularly relates to a rotary engine.

As the primary aim and object this invention contemplates the provision of a device 15 of the above character wherein the rotor is designed to rotate in either direction and is capable of receiving its impacts from different classes of fluids, such as steam, gas, water, compressed air, etc.

20 It is an additional object of this invention to provide a rotary engine wherein the rotor thereof is designed to rotate within the stator and the casing at a relatively high rate of speed in comparison to the 25 small amount and light pressure of the fluid used.

More particularly, this invention includes the provision of improved means for mounting the stator to provide a stator and a rotor 30 of an improved construction; and to provide improved means for mounting the rotor with respect to the casing and the stator.

Among the other aims and objects of this invention may be recited the provision of a 35 device of the character mentioned with a view to compactness, and in which the number of parts are few, the construction simple, the cost of production low and the efficiency high.

40 Other improvements and novel details in the construction and arrangement of the various parts of the apparatus will be brought out more in detail in the description to follow, which for a clear understanding 45 of the invention, should be considered in connection with the accompanying drawings forming a part hereof, and wherein is disclosed for the purpose of illustration a convenient and satisfactory embodiment of 50 the invention. It is to be noted in this connection that minor changes in the construction and arrangement of parts may be made without departing from the spirit of the

invention or the principle of operation of the various parts. 55

The invention is clearly illustrated in the accompanying drawings, in which:

Figure 1 is a side elevation of the invention;

Fig. 2 is a transverse section taken on line 2—2 of Fig. 1 in the direction in which the arrows point; 60

Fig. 3 is a sectional view taken on line 3—3 of Fig. 2 in the direction in which the arrows point; 65

Fig. 4 is an elevation looking toward the inside of the stator;

Fig. 5 is an elevation looking toward the inside of the rotor; and

Fig. 6 is a fragmentary perspective detail 70 of the rotor.

Similar reference characters indicate corresponding parts throughout the several views in the drawings.

Referring now, more particularly, to the 75 accompanying drawings there is provided a plurality of preferably three standards 1 mounted in spaced relation to each other while rigidly connected to one of the end standards and positioned between two of the 80 standards as indicated in Fig. 1 is the improved stator indicated in its entirety by the numeral 2. This stator consists of a circular body 3, the front face of which is provided with an annular channel 4 adjacent the outer 85 edge thereof. A shank 5 is formed integral with and central of the opposite face of the stator and is rigidly mounted on the upper end of the end standard 1 through the medium of a suitable bracket 6. Braces 7 are 90 also positioned between the stator and the end standard 1 to increase the rigidity of the stator with respect to the standard.

Cooperating with the improved stator is a 95 rotor indicated in its entirety by the numeral 8 and consisting of a circular body 9 in the front face of which and adjacent the outer edge thereof is formed spaced annular rims 10 connected at uniformly spaced intervals to each other through the instrumentality of 100 transverse blades 11 which form fluid receiving compartments. These rims are designed for reception in the channel and terminate adjacent the inner end thereof when the outer face of the body of the rotor is arranged in close relation with the outer face. 105

of the body of the stator for a purpose that will presently appear. A supporting shaft 12 projects centrally from the opposite face of the rotor and is reduced adjacent the rotor 5 forming a shoulder 13, the reduced end being journaled in a bearing 14 clamped to the upper end of the intermediate standard 1 by means of a bracket 15, while the reduced portion of the shaft is journaled adjacent 10 its outer end in the upper ends of the remaining standard 1, a bearing bracket 16 serving to facilitate the journaling thereof. A fly wheel 17 is mounted on the projecting end of the reduced portion of the shaft 12 15 and serves to facilitate the transmission of motion.

Preparatory to journaling the shaft 15 a sectional cylindrical casing 18 is employed being provided with a central opening 19 20 about which is formed a collar 20 which is designed for engagement with the reduced end 21 of the bearing 14 and also is arranged about the shaft 12 so that the side wall 22 will be positioned in close relation to the outer face of the body 9 of the rotor while the outer wall 23 is arranged in close relation with the outer edge of the rotor 8 and rigidly connected to the outer edge of the stator 2 as indicated in Fig. 3.

With a view toward providing suitable means for facilitating rotation of the rotor and the stator in the casing the outer edge of the body 9 of the rotor is provided with spaced circumferential grooves 24 which constitute braces for receiving ball bearings 25 also operating within the peripheral grooves 26 on the inner surface of the wall 23 of the casing which incidentally serve as braces. The outer edge of the body 9 of the rotor is 30 also provided intermediate the grooves 24 with another peripheral groove 27 in which is fitted the packing ring 28 designed for engagement with the adjacent surface of the wall 23 of the casing during rotation for preventing escape of fluid therebetween. Between the shoulder 13 in the outer edge of the reduced end of the bearing 14 are arranged a plurality of ball bearings 29 which engage the reduced portion of the shaft 12 in the inner 40 surface of the collar 21 to facilitate rotation of the rotor in the collar. In order to prevent the escape of fluids between the channel in the outer rim during rotation of the rotor the outer wall of the channel is 50 provided with spaced peripheral grooves 30 in which is fitted packing rings 31 for engagement with the outer rim, the arrangement being indicated in Fig. 3.

As intimated, improved means have been 60 provided for actuating the rotor in either direction. In reducing this feature of the invention to practice the intake manifold 32 is provided, the branches 33 thereof being fitted in transversely extending openings 34 65 in the body 3 of the stator adjacent the up-

per end thereof and which establish communication with the several compartments provided between the rims by the blades. The bottom of the channel is also provided with grooves 35 which extend from the opening as 70 indicated in Fig. 4 to assure of the incoming fluid being directed against the blades. Suitable valves 36 are operatively mounted in the branches 33 and when one is opened the other is closed to assure of the rotation 75 of the rotor in one direction and vice versa. The body of the rotor is also provided with an exhaust opening 37 adjacent the lower part thereof which leads from the channel for allowing the fluid to be exhausted 80 through the exhaust pipe 38 fitted in the opening.

The mode of operation may be reviewed as follows: Assuming that steam is used as a fluid for imparting impacts to the blades 85 11 of the rotor, one of the valves 36 is opened while the other is closed to allow steam to pass through the intake pipe 32 through the corresponding branch and thence through the corresponding openings 34 and 90 groove 35 so as to be directed against the adjacent blade and impart an impact thereto so as to assure of the rotation of the rotor. Of course as steam continues to flow into the channel impacts will be successively directed 95 against the several blades of the rotor during rotation thereof. By reason of the ball bearings 28 between the body of the rotor and the walls of the casing and between the shaft and the collar on the casing, an easy running 100 of the rotor is provided. Likewise by reason of the provision of the packing means 31 in the channel of the stator, and bearing against the outer ring on the rotor, steam is 105 prevented from escaping therebetween so as to assure of a maximum speed from a minimum pressure.

As many changes could be made in the above construction and many apparently widely different embodiments of this invention could be made without departing from the scope thereof, and it is intended that all matter contained in the above description or shown in the accompanying drawing shall be interpreted as illustrative and not in a 110 limited sense. It is also to be understood that the language used in the following claims is intended to cover all the generic and specific features of the invention herein described and all statements of the scope of 120 the invention, which, as a matter of language might be said to fall therebetween.

What is claimed is:

1. A rotary engine including a stator having an annular channel in one face thereof, 125 a casing surrounding the stator and arranged in spaced relation to the outer face thereof, a rotor embodying a cylindrical body mounted for rotation in the casing and adjacent the outer face of the stator, spaced 130

rings projecting from one face of the rotor and arranged within the channel in the stator, transverse blades positioned between the rings, an intake mounted in the stator 5 and through which fluid passes to impart impacts against the blades, and an exhaust leading from the stator.

2. A rotary engine including a stator having an annular channel therein, a rigidly 10 mounted casing surrounding the stator and rigidly connected thereto, a rotor rotatably mounted in the casing and in the channel in the stator, anti-friction means between the rotor and the casing for assuring an easy 15 rotation of the rotor, packing means between the rotor and the channel in the stator and between the rotor and the casing for preventing the escape of fluid, valve controlled fluid intake means mounted in the stator, 20 and exhaust means leading from the stator.

3. A rotary engine consisting of a rigidly mounted stator embodying a circular body having an annular channel in one face adjacent its outer periphery, a rigidly mounted cylindrical casing disposed about the outer edge of the stator and rigid therewith, a rotatably mounted shaft, a rotor carried by the inner end of the shaft and embodying a circular body rotatably disposed between the stator and the casing, spaced annular rings projecting from the front face of the body of the rotor and arranged in the channel in the stator, transverse blades connecting the rings, an intake connected to the

stator and in communication with the blades 35 in the rotor and an exhaust leading from the stator.

4. A rotary engine including a plurality of supporting standards, a stator rigidly connected to one of the standards and including a circular body having an annular channel in the outer face thereof and adjacent the outer edge, an intake manifold the branches of which are connected to the stator and arranged in communication with 40 the channel, valve means for controlling the passage of fluids through the branches of the manifold, an exhaust leading from the channel in the stator, a shaft rotatably mounted in the other standards, a pulley 45 wheel carried by one end of the shaft, a bearing carried by one of the standards and through which the shaft is journaled, a cylindrical casing carried by the bearing and disposed about and rigidly connected to the 50 stator, a rotor carried by the inner end of the shaft and embodying a circular body for rotating within the casing and adjacent to the stator, spaced annular rings projecting from the body and arranged for rotation in 55 the channel, transverse blades connecting the rings and against which impacts are made, anti-friction means between the shaft and the casing, anti-friction means between the casing and the rotor, and packing means 60 between the rotor and the stator.

In testimony whereof I affix my signature.
JAMES C. THOMPSON.
